UNITED STATES PATENT OFFICE.

ROLAND E. PERRIN, OF BROOKLYN, NEW YORK.

NECKTIE HOLDER.

Application filed November 30, 1927. Serial No. 236,691.

Although my invention in its preferred embodiment with the relative proportions shown in the accompanying drawings is primarily intended for use as a necktie clasp, 5 the invention in its broader aspects is applicable to fabric clamps of various kinds, or articles, such as buttons, adapted to be detachably secured to a fabric.

One object of my invention is to provide 10 means whereby the front part of the clamp, clasp, or the like may be firmly secured to the front end of a comparatively smooth pointed stud projected through the fabric.

A further object is to facilitate the firm 15 and rigid securing together of the front and back parts in various different spaced relationships and independent of the pressure applied to the fabric between said parts.

In carrying out my invention I provide a 20 back plate or base member having a pointed stud adapted to be forced or projected through one or more layers of fabric. The front member is provided with a collapsible clamp having threaded engagement with the front 25 member and clamping engagement with said stud whereby, after the clamp has been placed on the stud the front member may be rotated to collapse the clamp and grip the stud.

30 In using the device as a necktie clasp the back member or base plate may be placed inside of the front of the shirt and the stud may be forced through the fabric or through a button hole of the shirt and then through 35 the necktie. The front member may then be secured to the front end of the stud to hold the necktie in place. The front member may also serve to protect and conceal the front pointed end of the stud and may be ornamented by embossing, engraving, or rendered attractive or inconspicuous in any 40 other suitable manner.

In the accompanying drawings, there is illustrated merely one of the many forms 45 which my invention may assume within the scope of the appended claims.

In these drawings:

Fig. 1 is a central longitudinal section;

Fig. 2 is a transverse section on the line 50 2—2 of Fig. 1;

Fig. 3 is a perspective view of the back member or base plate;

Fig. 4 is a perspective view of the clamp, and

55 Fig. 5 is a section similar to a portion

of Fig. 1, but showing a slightly modified form.

In my improved construction, there is provided a back member having a base 10 and a centrally disposed upstanding pointed 60 stud or pin 11. The base may be of any desired shape, although to facilitate holding it during the rotation of the front member as hereinafter referred to the base may be polygonal rather than circular in form. The 65 upper or outer face of the base may have pins, projections or the like 12 which may engage with the fabric through which the stud is projected and prevent rotation of the back member. These pins or projections are 70 preferably comparatively low in height and are preferably slightly pointed to facilitate non-slipping engagement with the fabric. The stud is preferably square in cross-section, although it may be of any other non-circular form, whereby the clamp herein-after referred to is prevented from rotating 75 on the stud.

The front member includes a plate 13 provided with a central aperture within which 80 is mounted a clamp 14. The clamp is of such a character that when moved endwise in the aperture of the plate 13 it is collapsed or contracted so as to grip the stud 11 which sticks through or into an aperture in the center of the clamp. As shown the clamp has an annular end wall 15 and a body portion 16 cut lengthwise by radial slots 17 so as to subdivide the body into a plurality of sections. 85

For a four-sided stud there may be four 90 of these sections and the center hole in the clamp may be of such size that the edges of the stud enter the slot to prevent relative rotation of the clamp and the stud. 95

The end wall 15 is made comparatively thin so as to permit limited radial relative movements of the several sections of the body.

The clamp has threaded engagement in 100 the center aperture of the plate 13 and this aperture is preferably tapered so that as the plate is screwed down on the clamp and away from the end wall 15, the sections of the body 16 will be forced toward each other to rigidly and firmly clamp the stud 11. The resiliency of the end wall 15 is such that when the plate is screwed in the opposite directions, the sections of the body will separate and liberate the stud. 105

The flange or end wall 15 serves an additional function in that it is of larger diameter than the body portion so that it may engage with the top or outer surface of the 5 plate 13 to form a stop and prevent the separation of the parts.

In assembling, the ends of the sections of the body 16 may be forced together to such an extent that they may be screwed into the 10 smaller end of the aperture in the plate.

The front member also preferably includes a second plate which serves as a cover or front wall to conceal the clamp and the stop. This is shown as of circular convex 15 form with its edges spun or forced under the edge of the plate 13 to permanently connect the two parts. This front plate need not be of metal, although the other parts preferably are of that material. The front plate may 20 be celluloid or of any other material to give the desired appearance. The arching or curving of the front plate 18 provides adequate space for the various adjusted positions of the stud 11. The center portion may 25 have a recess 19 to receive the end of the stud and to resist any tilting of the front member.

From the standpoint of mechanical operation the front plate 18 might be omitted, but 30 it is preferably employed as a cover or protection for the other parts.

After the base 10 has been placed inside of the shirt and the stud 11 forced out through the fabric of the shirt and the fabric of the 35 necktie, the clamp is slipped on to the stud to the desired distance and the plate 13 is rotated to tighten the clamp. As the pins or projections 12 engage the fabric and prevent rotation of the base, it is not necessary 40 to otherwise hold this base against rotation, although this may be done if any considerable amount of force is to be employed in tightening the clamp.

In Fig. 5 I have shown a slightly modified 45 construction in which the clamp 14^a has an inturned flange or lip 20 at its lower open end and the stud 11^a has a shoulder 21 beneath which the flange or lip 20 may engage. In this construction, when the clamp is 50 tightened, the front member is held in place, not only by the frictional gripping of the stud, but also by the positive locking of the clamp beneath the shoulder. This shoulder should not be so high or sharp as to interfere 55 with the free passage of the stud through the fabric. The taper of the threads is also shown in the opposite direction so that the plate is screwed up instead of down in clamping.

60 The center portion of the plate 13 within which the clamp is mounted is shown of considerably greater thickness than the outer or marginal portion of the plate. It will be obvious that this center portion may constitute a shank and the entire device used as

a button, the free edge of the plate 13 being spaced from the fabric to a distance equal to the length of said shank.

Having thus described my invention, what I claim as new and desire to secure by Letters Patent is:

1. A device of the class described, including a back member having a smoothed surfaced, non-cylindrical pointed stud adapted to be forced through one or more layers of fabric, a front plate, and a collapsible clamping member adapted to telescope on said stud but held against rotation in respect thereto and having tapered threaded engagement with said plate, whereby upon the 75 rotation of the plate, the clamping member may be rigidly secured to said stud.

2. A device of the class described, including a base having a smoothed surface, non-cylindrical pointed stud adapted to be forced through one or more layers of fabric, and a front member, including two relatively rotatable parts having tapered threaded connections, the inner of said parts having an 80 aperture adapted to receive said stud but held against rotation in respect thereto and having wall sections adapted to be forced into rigid engagement with said stud.

3. A device of the class described, including a back member having a smoothed surface, non-cylindrical pointed stud adapted to be forced through one or more layers of fabric, a front plate having a tapered threaded aperture, a clamping member disposed within said aperture and having a 95 threaded exterior and a central passage to receive said stud but held against rotation in respect thereto, the wall of said member being formed of relatively movable sections 100 adapted to be moved inward radially upon 105 the relative rotation of said plate and said clamping member.

4. A device of the class described, including a back member having a smooth surfaced, non-cylindrical pointed stud adapted 110 to be forced through one or more layers of fabric, a front plate having a tapered threaded aperture, a clamping member disposed within said aperture, and having a 115 central passage to receive said stud but held against rotation in respect thereto, the wall of said member being formed of relatively movable sections adapted to be moved inward radially upon the relative rotation of 120 said plate and said clamping member, and a plate having its marginal portions secured to the margin of said first mentioned plate and serving to conceal said clamping member and the front end of said stud.

5. A device of the class described, including two members adapted to secure one or more layers of fabric therebetween, one of said members having a pointed stud adapted to project through the fabric and having longitudinally extending edges and the 130

other having a collapsible wall for engagement with said stud but held against rotation in respect thereto, said wall and said last mentioned member being relatively rotatable to effect the clamping action.

6. A device of the class described, including a plate having a sharp pointed stud adapted to project through one or more layers of fabric, a series of projections 10 adapted to engage with the surface of the

fabric to prevent rotation of said plate, said stud being square in cross-section, a collapsible clamp adapted to telescope with said stud, and a front member rotatable on said clamping member to effect engagement of 15 the clamping member with the stud.

Signed at New York, in the county of New York and State of New York this 28th day of Nov. A. D. 1927.

ROLAND E. PERRIN.
